MECHANICAL TUNING ARRANGEMENT FOR
DUAL HELIX WINDING ANTENNA (COMPACT ANTENNA, 30-76 MEGACYCLES)Robert M. Moorehead, Richardson, Tex., assignor to
Collins Radio Company, Cedar Rapids, Iowa, a
corporation of IowaFiled Dec. 10, 1965, Ser. No. 513,039
8 Claims. (Cl. 343—877)

ABSTRACT OF THE DISCLOSURE

A compact variable inductor arrangement is achieved by using a reel of flexible conducting tape in conjunction with a helically grooved cylinder member. A second cylinder with longitudinally extending slot is placed concentrically about the grooved cylinder. A clamping means attached to the end of the flexible tape and cooperating both with the outer cylinder slot and the inner cylinder groove, forces a withdrawal of tape from the supply as the inner cylinder is rotated relative to the outer cylinder.

This invention relates in general to antennas and in particular to electrically small antennas tunable over a wide frequency range.

The copending patent application of Richard C. Fenwick entitled, "Electrically Small Antenna Tunable Over a Wide Band," Ser. No. 508,482 filed Nov. 18, 1965, assigned to the assignee of the present invention, discloses an antenna which is electrically small and which consists of a pair of windings mounted on cores spaced side by side. The present invention comprises an actual embodiment of such an antenna which might be used, for example, in aircraft installations.

An object of the present invention is to provide an electrically small antenna which may be tuned in a simple manner.

Another object of this invention is to provide an antenna consisting of a pair of helically grooved insulating drums which are rotatably mounted within a pair of insulating slotted cylinders and on which flexible tape may be selectively wound to provide an electrically small antenna.

Another object of this invention is to provide a compact electrically small antenna which may be easily tuned over a wide frequency range.

Further objects, features, and advantages of this invention will become apparent from the following description and claims when read in view of the accompanying drawings, in which:

FIGURE 1 is a top, partially cut-away view of the antenna according to this invention;

FIGURE 2 is an enlarged cut-away view of one of the tape laying-on portions of the antenna;

FIGURE 3 is an enlarged detail view of the tape holding shorting bar; and

FIGURE 4 is a top schematic view of the antenna.

FIGURE 1 is a top view which illustrates a radome 10 which is transparent to radiant energy but which is capable of protecting the antenna from ice and moisture. Three partitions 11, 12 and 13 are formed within the radome and a pair of drums 14 and 16 are rotatably supported within the radome between partitions 12 and 13. The drums 14 and 16 are formed with helical grooves. A first slotted cylinder 17 is supported by standoffs 18 and 19 from the wall of the radome and has a longitudinal slot 21 which extends down the cylinder 17.

A second slotted cylinder 22 is supported from the radome by standoffs 23 and 24 and is formed with a slot 26. The grooved drums 14 and 16 are mounted on shafts 27 and 28, respectively, which carry pulleys 29 and 31.

2

A motor 32 is mounted on plate 11 and its output shaft 33 carries a gear 34 which drives a gear 36 rotatably supported on a shaft 37 which is supported by partition 11. The shaft 33 carries a pulley 38 which drives the pulley 29 through the belt 39. The shaft 37 carries a pulley 41 which drives the pulley 31 through a belt 42.

A pair of tape reels 43 and 44 are insulatingly supported from plate 12 by spiral springs 46 and 47 and carry flexible conducting tapes 48 and 49 thereon. The tape passes from the reel 44 over a pay-out roller 51 which is rotatably supported on an arm 52 which is attached to the end 53 of the grooved drum 16. A guide roller 54 is rotatably supported by shaft 56 from a stand-off 57 attached to the end 53 of drum 16. The roller 54 engages the edge 58 of the tape 49 to hold it on the reel 44. The rollers 51 and 54 are mounted on opposite sides of the drum 16. Likewise, the drum 14 carries a pay-out roller 61 and a guide roller 62 on opposite sides of its end. The details of the pay-out means are shown relative to drum 16 in FIGURE 2 and the construction of the pay-out and take-up mechanism for drum 14 is similar.

The ends of the tapes 48 and 49 are attached to movable clamps 63 and 64 which ride in the slots 21 and 26 of the slotted drums 17 and 22. A shorting bar 66 joins the clamps 63 and 64.

As best shown in FIGURE 3, the clamp 64 has a lower portion 67 which is formed with a pair of jaws 68 and 69 into which the end 71 of the tape 49 is clamped. The upper portion of the member 64 is formed with a rectangular portion 72 which fits in the slot 26. The shorting bar 66 is electrically connected to the end 71 of the tape 49 through a conducting portion 73 which extends downwardly to the jaws 68 and 69. Likewise, clamp 64 is attached to the end of tape 48.

In operation, if it is desired to tune the antenna which comprises the tapes mounted about the drums 14 and 16, the motor 32 is energized to rotate the drums. As the drums 14 and 16 rotate, the helical grooves in the drums 40 cause the members 63 and 64 to move longitudinally in slots 21 and 26. For example, if the cylinders are rotated in a first direction, the members 63 and 64 will move to the right relative to FIGURE 1 and will lay electrically conducting tapes 48 and 49 in the grooves 45 of the grooved drums resulting in an increase in the number of turns of inductance. It is to be noted that the grooves in the drums 14 and 16 are so formed such that the blocks 63 and 64 move in the same direction to respectively lay on more turns or remove turns.

The pay-out rollers 61 and 51 rotate with the drums and remove conducting tape from the reels 43 and 44 as the members 63 and 64 move to the right in slots 21 and 26. The grooved drums 14 and 16 and slotted cylinders 17 and 22 are formed of an insulating plastic which has very low friction and the conducting tape which might be, for example, made of silver-plated beryllium copper slides easily in the grooves as the drums are rotated. The conducting tape has a tendency to easily assume a spiral position as it is taken off the reels 43 and 44 which facilitates its slipping easily in the grooves of the cylinder to allow tuning.

A feed conductor 76 may be insulatingly supported from the partition 12 to engage the metallic reel 43 and a similar conductor (not illustrated) may be made to engage the tape reel 44. The conductors allow a feed line 77 to be connected to the tape reels for feed line and ground plane connections. As best shown in the top view of FIGURE 4, a suitable generator E may be connected to lead 77 to energize the antenna.

In an actual embodiment, two cylinders 18 inches long by 3 inches in diameter were mounted side by side. The length of the antenna was varied by rotating the

grooved drums and threading the antenna (conductor) onto the drums. The conducting ribbons or tapes are stored on stationary reels located at the end of the drums.

The outer slotted cylinders are held stationary and serve two functions:

(1) Encloses the tape, thus maintaining constant diameter and constant length

(2) Guide the ends of the tapes linearly while the grooved drums rotate.

One-half inch wide tape was spaced one-half inch apart on the drums with a maximum of 18 turns on each drum. Therefore, if the drums rotate at a maximum speed of 200 r.p.m., approximately 6 seconds will be required to change the frequency from 30 to 76 mc.

The antenna mechanisms were enclosed in a radome with maximum overall dimensions of 24 inches long by 6 inches high by 7 inches wide. These dimensions include contouring for aerodynamic streamline.

The grooved drums and slotted cylinders were made of Teflon, which provides excellent electrical properties and a low coefficient of friction with the copper tape.

It is seen that this invention comprises a simple electrically small antenna capable of being tuned over a broad frequency range and although this invention has been described with respect to a particular embodiment thereof, it is not to be so limited, as changes and modifications may be made therein which are within the spirit and scope of the invention as defined by the appended claims.

I claim:

1. A pair of variable inductors coupled together comprising a pair of insulating drums rotatably supported parallel to each other, a pair of fixed slotted cylinders extending over said drums, a first reel of flexible conducting tape mounted at the end of the first rotating drum, a second reel of flexible tape mounted at the end of the second rotating drum, a first clamp attached to the end of the first conducting tape and mounted in the slot of the first slotted cylinder, a second clamp attached to the end of the second tape and mounted in the slot of the

second slotted cylinder, and an electrical conductor connected between the first and second clamps.

2. In apparatus according to claim 1 a driving means coupled to the first and second drums to rotate them.

3. In apparatus according to claim 1, a pay-out roller attached to the end of the first drum adjacent the first reel and the first flexible tape passing over said pay-out roller onto the first drum.

4. A variable inductor comprising a drum of insulating material, flexible conducting tape, an insulated slotted cylinder mounted about the drum, a clamp mounted between the drum and cylinder within the slot, means for rotating the drum relative to the cylinder, means for moving the clamp in the slot as the drum rotates relative to the cylinder, and said flexible conducting tape attached to the clamp.

5. In apparatus according to claim 4 wherein the means for moving the clamp in the slot comprises a spiral groove formed in the drum.

6. In apparatus according to claim 5, a reel for holding the flexible conducting tape adjacent the end of the drum, a lay-on mechanism attached to the drum adjacent the reel and the flexible tape passing from the reel over the lay-on mechanism to the drum.

7. In apparatus according to claim 6 wherein said lay-on mechanism comprises a roller supported from the drum.

8. In apparatus according to claim 6 wherein the reel is supported for limited rotary motion adjacent the end of the drum.
